MACHINE FOR MAKING VALVE STEM
BASES

William F. Goff, Akron, and Ewald F. Tobold, Cleveland, Ohio, assignors to The Dill Manufacturing Company, Cleveland, Ohio, a corporation of Ohio

Application February 17, 1936, Serial No. 64,210

15 Claims. (Cl. 28—1)

This invention relates to a machine for fashioning or wrapping a cord base on the inner end of a valve stem such as is employed with pneumatic tires for motor vehicles or other inflatable articles.

An object of the invention is to provide a machine of the character specified above which will efficiently fashion or wrap a cord base on the end of a valve stem and which is semi-automatic in its operation.

A further object is to provide a machine of the character specified which is of simple construction and which is capable of fashioning or wrapping a cord base on the inner end of a valve stem quickly and efficiently.

Another object is to provide a machine of the character specified wherein the turns of the cord of the cord base about the inner end of the valve stem progress from a point intermediate the ends of the stem to the inner end thereof.

Further and additional objects and advantages not specifically referred to above will become apparent hereinafter during the detailed description of an embodiment of the invention, which is illustrated in the accompanying drawings, wherein

Fig. 1 is a vertical sectional view through the machine and shows a valve stem in position therein to have a cord base fashioned or wrapped on its inner end;

Fig. 2 is a diagrammatic plan and sectional view taken substantially on line 2—2 of Fig. 1 looking in the direction of the arrows and showing the relationship between certain of the operative parts of the machine;

Fig. 3 is a sectional view taken substantially on line 3—3 of Fig. 1, looking in the direction of the arrows;

Fig. 4 is a view illustrating the manner in which the cord base is fashioned or wrapped on the inner end of the valve stem and shows the condition of the base and the operation of fashioning the same substantially half way completed, and

Fig. 5 is a perspective view of a valve stem with the completed cord base fashioned or wrapped thereon.

The cord base and the method of wrapping or fashioning the same on the inner end of the valve stem is fully disclosed in the copending application of A. E. Bronson and William F. Goff, Serial No. 56,220, filed December 26, 1935, and the machine of the present invention constitutes one means by which such base can be fashioned

and the method carried out semi-automatically and mechanically.

The machine comprises spaced parallel frame members 10 and 11 suitably interconnected and interbraced in their spaced parallel relationship by transverse members, such as the member 12 shown in Fig. 1. A shaft 13 is rotatably supported in the frame member 10 and is provided with collars 14 and 15 secured to the shaft on opposite sides of the frame member 10 to prevent endwise movement of the shaft. The outer end of the shaft 13 has fixed thereto a pulley 16, while the inner end of the shaft has fixed thereto a bevel gear 17. The shaft 13 can be driven from any suitable source of power by a belt extending around the pulley 16 although it should be understood that motive power can be transmitted to the shaft 13 in any other desirable manner. Intermediate the collar 14 and the frame member 10 a disk 18 is mounted on the shaft 13 and is keyed thereto to rotate therewith. The disk 18 is provided with a headed pin 19 located adjacent the circumference of the disk and having its head arranged on the inner side of the disk. The pin 19, when the shaft 13 and the disk 18 are rotating, engages in the slots of Geneva wheels 20 and 21. The Geneva wheels 20 and 21 are each provided with four radially extending slots 20a and 21a spaced 90° apart. The Geneva wheel 20 is keyed to a shaft 22 rotatably supported in the frame members 10 and 11 and located to one side and forwardly of the shaft 13, as viewed in Fig. 2. The Geneva wheel 21 is rotatably mounted on a stub shaft 23 carried by the frame member 10 and has fixed thereto a gear 24 of substantially the same diameter as the Geneva wheel and arranged on the inner face thereof. The purpose of the gear 24 will later be explained. The Geneva wheels 20 and 21 are so arranged that the slots 20a and 21a respectively lie with respect to each other at the commencement of the operative cycle at angles other than 90°, as clearly shown in Fig. 2, for a purpose later to become apparent.

The shaft 22 inwardly of the frame member 11 has fixed thereto a large gear 25 which meshes with a pinion 26 fixed to the inner end of a short shaft 27 rotatably mounted in the frame member 11 and lying substantially in line with the shafts 13 and 23, as clearly shown in Fig. 2. The outer end of the shaft 27 has fixed thereto a bevel gear 28 which meshes with a similar bevel gear 29 fixed to the end of a shaft 30 that is rotatably supported in suitable bearing brackets 55

31 and 32 extending outwardly from the frame member 11, the shaft 30 being held against endwise movement by the sleeve of the gear 29 and by collars 31a and 32a keyed to the shaft and engaging the ends of the brackets 31 and 32, respectively.

It will be seen that during each revolution of the shaft 13 in the direction indicated by the arrow in either Fig. 1 or Fig. 2, the pin 19 of the disk 18 will engage in one of the slots 20a of the Geneva wheel 20 and impart a quarter of a revolution to the Geneva wheel, shaft 22 and gear 25. The ratio between the gear 25 and the pinion 26 is such that for each quarter revolution of the gear 25 the pinion will make a complete revolution, as will also the gears 28 and 29 and the shaft 30. It will thus be observed that during each revolution of the shaft 13 there will be a complete revolution of the shaft 30 through the mechanism just referred to, but that such complete revolution of the shaft 30 is completed a substantial time prior to the completion of the revolution of the shaft 13.

Adjacent the bracket 32 and to the right thereof, as viewed in Fig. 1, a locking disk 33 is keyed to the shaft 30 to rotate therewith and said disk is provided in its periphery with a conical recess 33a, later to be referred to. The left hand end of the shaft 30, as viewed in Fig. 1, extends into a recess 34a formed in the end of an elongated work holding member 34 which, at its opposite end, is provided with a recess 34b to receive and hold a valve stem 35. The latter end of the member 34, that is the left hand end as viewed in Fig. 1, is provided with an enlarged cylindrical head 34c having a plurality of circumferentially spaced axially extending openings in which are slidably mounted pins 36, the left hand ends of which project to the left of the head 34c and are provided with cylindrical grooves 36a, while the opposite ends of the pins, as viewed in the drawings, extend toward the right away from the head 34c and have formed at their tips shoulders or heads 36b. Springs 37 surround the pins and abut at their opposite ends the heads 34c and 36b. It should be noted that the pins 36 are arranged concentrically with respect to the recess 34b and although sixteen of the pins have been illustrated herein, various numbers could be employed as desired.

A spring 30a surrounds the shaft 30 between the right hand end of the member 34 and the collar 32a and tends to urge the member 34 toward the left, as viewed in Fig. 1. A member 38 is keyed to the member 34 adjacent its right hand end and is provided on its periphery with ratchet teeth 38a. The members 38 and 34 are each provided with a radially extending bore arranged in alignment with each other with the bore in the member 34 slidably carrying a shoe 39 that frictionally engages the shaft 30 and is held in such frictional engagement by means of a spring 39a arranged in the bores and abutting at its outer end an adjustable nut 39b screwed into a counterbore formed in the member 38 in alignment with the bore therein. It will thus be seen that the member 38 and the member 34 are frictionally connected to the shaft 30 to rotate therewith, but when the shaft 30 is held against rotation these members can be rotated independently thereof inasmuch as a slippage occurs therebetween. The member 38 is provided at its left hand end, as viewed in the drawings, with an axially extending headed pin 38b which engages 75 with the cam 40b on one face of a cam member

40 independently rotatably mounted on the member 34 but normally rotating with the member due to the frictional driving connection affected therebetween by means of a spring pressed friction shoe 40a engaging the periphery of the member 34 and similar to the shoe 39 previously described. The cam member 40 is provided on its opposite faces with a cam 40b which engages the pin 38b, as previously explained and with a cam 40c which engages the heads 36b of the pins 36 10 carried by the member 34. The cam member 40 is held against endwise movement by suitable stop members 41 located on opposite sides of the cam member and carried by the frame member 11. The periphery of the cam member 40 has formed 15 therein a conical recess 40d adapted to cooperate with a locking pin, later to be referred to, wherefore when the pin engages in the recess the cam member will be held against rotation while, due to the slippage of the friction shoe 40a the member 34 will be free to rotate within the cam member.

The gear 17 on the inner end of the shaft 13 meshes with a gear 41 fixed to the end of a rotatable shaft 42 mounted in suitable supports 43 25 and 44 carried by the frame member 11. On the opposite end of the shaft 42 from the gear 41 a cam 45 is fixed to the shaft, to rotate therewith, while intermediate said cam 45 and support 43 a similar cam 46 is fixed to the shaft to rotate 30 therewith. Intermediate the supports 43 and 44 a third cam 47, similar to cams 45 and 46, is fixed to the shaft 42 to rotate therewith, it being noted that the shaft 42 is geared to the shaft 13 with a one to one ratio so as to rotate at the same 35 speed.

The cam 45 which, as has been stated, is similar to the cam 46, see Fig. 3, has its periphery in engagement with a plunger 48 slidably carried in the frame member 11 and provided with a conical head adapted to seat in the conical recess 40d of the cam member 40 when the inner end of the pin is in engagement with the high point of the cam 45 to lock the cam member 40 against rotation. A spring 49 surrounds the plunger 48 and acts to 45 cause the inner end of the plunger to follow the periphery of the cam.

The cam 46 has its periphery in engagement with the inner end of a lever 50 that is pivotally connected intermediate its ends to a bracket carried by the frame member 11, and said lever 50 extends through an elongated opening in the frame member 11 to the opposite side thereof from the bracket and is free to be rocked in its pivotal movement within the opening, see Fig. 3. The outer end of the lever 50 has pivotally connected thereto a pawl 51 which engages with the ratchet teeth 38a on the member 38 to index the latter at a predetermined time in the operative cycle. A spring 52 anchored at its opposite ends to the 60 frame member 11 and to the outer end of the lever 50 maintains the inner end of the lever in engagement with the periphery of the cam 46.

The cam 47 which, as has been stated, is similar to the cam 46, see Fig. 3, has its periphery in engagement with a plunger 53 extending through the frame member 11 and having at its outer end a conical head adapted to seat in the conical recess 33a of the member 38 to lock the shaft 30 against rotation. A spring 54 surrounds the 70 plunger 53 and maintains the inner end of the plunger in contact with the periphery of the cam.

The cams 45, 46 and 47 although identical are so positioned on the shaft 42 in assembling the machine that the cams 45 and 47 will act at the 75

same time to move the plungers 48 and 53, respectively, upwardly so that the heads of the plungers engaged in the recesses 40d and 33a and lock the cam member 46 and the member 33 and shaft 30 against rotation. The cam member 46 is so positioned relative to the cams 45 and 47 that its high point comes into engagement with the lever 50 to rock the latter and index the member 38 just after the high points of the cams 45 and 47 have engaged the inner ends of the plungers 48 and 53 and forced the same upwardly, the interval, however, being so slight that the cams may be said to act substantially simultaneously.

When the high point of the cam 46 engages the inner end of the lever 50 said lever is locked against the action of the spring 52 and in a direction such that the pawl 51 in engagement with the ratchet teeth 38a of the member 38 imparts a rotational or indexing movement to said member 20 equal to one ratchet tooth space.

A hollow spindle 55 is rotatably supported on a shaft 56 fixedly mounted in the frame member 10 and extending across the machine to the outer side of the frame member 11. The spindle 55 adjacent the frame member 11 is provided with an enlarged head 57 having at its outer end a circumferential flange 57a engaging the outer side of the frame member 11 while on the inner end of the head 57 a plate 58 is fixed thereto by means 30 of a nut 59 screwed on the spindle and a pin 60 extending through the plate and into the head and preventing relative rotation between the head and plate, said plate 58 engaging the inner side of the frame member 11, and together with 35 the circumferential flange 57a on the outer end of the head preventing endwise movement of the spindle while allowing rotation thereof. The shaft 56 is provided with a circumferential flange 61 engaging the inner side of the frame member 40 10, while a nut 62 screwed on the end of the shaft cooperates with the flange 61 to clamp the shaft in fixed position in the frame member 10.

A gear 63 is keyed to the spindle 55 and meshes with the gear 24 associated with the Geneva 45 wheel 21. The ratio between the gear 63 and the gear 24 is such that for each complete revolution of the shaft 13 and each quarter of a revolution of the gear 24 and Geneva wheel 21 the gear 63 and the spindle 55 make two complete revolutions. Reference to Fig. 2 will clearly show that 50 the spindle makes two revolutions for each revolution of the shaft 13 but that the revolutions of the spindle take place during one quarter of the complete revolution of the shaft 13.

55 A table 64 is fixed to the spindle 55 and revolves therewith and said table is provided with a pin or fixed shaft 65 upon which a spool of cord 66 is mounted. The free end of the cord 66 passes through a guiding member 67 fixed to the spindle 55 and revolving therewith and having a spring-pressed plunger 68 to maintain tension on the cord. The cord passes through a guiding sleeve 69 and through aligned openings in the plate 58 and the head 57 of the spindle, as clearly illustrated in Fig. 1, and thence over to adjacent the pins 36.

The frame member 10 on its outer side is provided with a fixed pin or shaft 70 on which is mounted a spool of cord 71, which has its free end 70 extending through a guiding and tensioning member 72 mounted on the outer side of the frame member 10 and similar to the member 67. The free end of the cord 71 passes through a bore or passage formed in the shaft 56 and extends to the outer side of the frame member 11, whence it can

be secured to the end of the valve stem 35 carried by the member 36.

The operation of the machine is as follows:

With the member 34 in its most left-hand position, at which time the left-hand end of the shaft 30 is at its maximum distance from the inner end of the recess 34a and the pin 38b of the member 38 engages the cam 40b at its lowest point, a valve stem 35 is positioned in the recess 34b of the member 34 and the cord 71 is passed through the shaft 10 56 and its free end tied around the valve stem adjacent but spaced from the end of the latter, as indicated at 71a in Fig. 1. The free end of the cord 66 is passed through the head 57 of the spindle 55 and back of the cord 71, such free end either 15 being held by the operator or being tied to a convenient part of the machine. At this time it will be understood that the plungers 48 and 53 are withdrawn from engagement with the members 40 and 33 and that the lever 50 is in engagement with 20 a low point on the cam 46.

It will be further understood that the pin 19 on the disk 18 is in such position that it is ready to enter one of the slots 21a of the Geneva wheel 21, as shown in Fig. 2. The machine now being set 25 in operation, the rotation of the shaft 13 in the direction of the arrows rotates the disk 18 and the pin 19 carried thereby enters the slot 21a in the Geneva wheel 21 and imparts a quarter turn thereto and to the gear 24 in the direction indicated by the arrow in Fig. 2.

As previously explained, the ratio between the gear 24 and the gear 63 is such that the latter will make two complete revolutions for each quarter turn of the former, so that it will be seen the 35 spindle 55 will be given two complete revolutions since the gear 63 is keyed thereto. The two complete revolutions of the spindle 55 wraps or turns the extending free end of the cord 66 twice around the cord 71, as will be clearly understood, it being 40 remembered that the table 64 and the guiding and tensioning member 67 rotate with the spindle. When the pin 19 leaves the slot 21a in the Geneva wheel 21, there is a short moment when neither the shaft 30 nor the spindle 55 is driven, as indicated by the curved arrow line designated "Rest" in Fig. 2. Following this so-called "rest" period, the pin 19 now enters one of the slots 20a in the Geneva wheel 20 and said Geneva wheel is given a quarter turn in the direction indicated by the 50 arrow in Fig. 2. At this time the Geneva wheel 21 and, of course, the spindle 55 are idle. The quarter turn imparted to the Geneva wheel 20 also rotates the gear 25 fixed on the shaft 22 through a quarter turn, and since said gear is in mesh with 55 the gear 26 and the latter makes one complete revolution for each quarter revolution of the gear 25, the bevel gears 28 and 29 will each be rotated one turn, as will the shaft 30, and due to the frictional driving connection between the shaft 30, 60 and the member 34 the latter will also rotate one turn, it being noted that the member 38 moves with the member 34 as it is keyed thereto and that the pawl 51 will merely click over the ratchet tooth 38a.

It will also be remembered that due to the frictional driving connection between the member 34 and the cam member 40 the latter will rotate one turn with the member 34. The complete revolution of the member 34 results in the cord 71 being 70 wrapped around the most outwardly extending pin 36, that is, the pin which has its inner end in engagement with the high point of the cam 40c, and then around the end of the valve stem 35. At this time the pin 19 leaves the slot 20a in the Geneva 75

wheel 20 and driving movement to the shaft 30 ceases, it being remembered that the spindle 55 is also idle at this time. The indexing period, as indicated by the curved arrow line marked "Indexing time" in Fig. 2, commences simultaneously with the ceasing of the driving movement to the shaft 30 and the high points of the cams 46 and 47 force the plungers 48 and 53 outwardly and bring the conical heads thereof into the conical recesses in the cam member 40 and the member 33, respectively. The plunger 48 thus locks the cam member 40 against rotation while the plunger 53 locks the shaft 30 against rotation. As the cam member 40 and the shaft 30 are locked, the high point of the cam 46 comes into engagement with the lever 50 and rocks the same in a direction such that the pawl 51 indexes the member 33 the distance of one ratchet tooth, and since said member 33 is keyed to the member 34, the latter is also indexed a distance of one ratchet tooth or the distance between adjacent pins 36.

It will be understood that, during the indexing of the member 33 and the member 34, a slippage takes place between the member 34 and the shaft 30 and the cam member 40 which are only frictionally operatively connected thereto. The indexing of the member 34 brings the next pin 36 into position so that its inner end is in engagement with the high point of the cam 46c on the cam member 40 and the opposite end of such pin is now in the most outward position with respect to the corresponding ends of the other pins. It will be understood that the purpose of having the left-hand end of said pin in its most outward position is to enable the cord 71 to be wrapped around it and the valve stem without contacting the corresponding ends of the other pins 36 which have their right-hand ends in engagement with the low points on the cam 46c.

40 The indexing of the member 33 progressively moves the pin 36b along the cam 46b from the lowermost point of the cam toward the highest point thereof, with the result that the member 34 and the member 33 are moved slightly toward 45 the right, as viewed in the drawings, and against the action of the spring 30a. As soon as the indexing has been completed, the conical heads on the plungers 48 and 53 move out of the conical recesses 49d and 33a while the pin 18 on the disk 18 enters another of the slots 21a of the Geneva wheel 21 to impart to the disk and to the gear 24 a quarter turn to again wrap the cord 66 twice around the cord 71 as has been previously explained.

55 From now on the operation is repeated automatically in the same sequence until the cord 71 has been wrapped around each of the pins 36 and the valve stem to provide a plurality of radially extending loops and the cord 66 has 60 made two turns around the cord 71 adjacent each of the pins 36, that is, around the outer end of each loop.

It will be seen that due to the indexing of the member 33 the pin 36b carried thereby gradually travels from the low point of the cam 46b to the high point thereof and moves the member 34 axially toward the right as viewed in Fig. 1, the result being that the turns of the cord 71 about the valve stem gradually progress from the illustrated position in Fig. 1 toward the end of the valve stem. When the operation has been completed, the machine is stopped, the cord 66 severed adjacent the head 57 and the ends thereof tied in a knot, as indicated at 71a in Fig. 5.

75 Similarly, the end of the cord 71 is severed ad-

jacent the head 57 and the end thereof which is connected to the base is looped around the valve stem and tied as indicated at 71b. The operator now removes the valve stem from the member 34 and the outer ends of the loops of the cord 5 base which have been fashioned on the stem from the pins 36. The character of the base and the manner in which it is applied to a tire tube is clearly illustrated and described in the above-mentioned co-pending application of A. E. Bronson and William F. Goff, Serial No. 56,220, and need not be further referred to herein.

It will be seen that a machine embodying the present invention constitutes an efficient and semi-automatic means for fashioning the cord 15 base directly on the end of the valve stem. It will be further noted that such a machine is composed of a relatively few number of parts, may be readily assembled and operated, and will enable valve stems to be economically manufactured.

Although a preferred embodiment of the invention has been illustrated and described herein, it should be understood that the invention is susceptible of various modifications and adaptations within the scope of the appended claims.

Having thus described my invention, I claim:

1. A machine for fashioning a cord base directly on the end of a valve stem comprising means for forming a plurality of radially extending cord loops having their inner ends wrapped about the valve stem, and means for interconnecting the outer ends of said loops with a circumferentially extending cord turned a plurality of times about the outer end of each loop. 35

2. A machine for fashioning a cord base directly on the end of a valve stem comprising means for forming from a continuous cord a plurality of radially extending loops having their inner ends wrapped about the valve stem, and means for interconnecting the outer ends of said loops with a circumferentially extending continuous cord turned a plurality of times about the outer end of each loop. 40

3. A machine for fashioning a cord base directly on the end of a valve stem comprising a valve stem holding member having a plurality of circumferentially spaced pins arranged concentrically with respect to the stem, means for intermittently rotating said member through a complete revolution to successively wrap a cord about the valve stem and each of said pins to form a plurality of radially extending loops, and means for indexing said member one pin space intermediate each rotation of the member. 45

4. A machine for fashioning a cord base directly on the end of a valve stem comprising a valve stem holding member having a plurality of circumferentially spaced pins arranged concentrically with respect to the stem, means for intermittently rotating said member through a complete revolution to successively wrap a cord about the valve stem and each of said pins to form a plurality of radially extending loops, 60 means for indexing said member one pin space intermediate each rotation thereof, and means for gradually moving said member axially endwise during the operation of the machine. 65

5. A machine for fashioning a cord base directly on the end of a valve stem comprising a valve stem holding member having a plurality of circumferentially spaced pins arranged concentrically with respect to the stem, means for intermittently rotating said member through a 70

complete revolution to successively wrap a cord about the valve stem and each of said pins to form a plurality of radially extending loops, means for turning a second cord a plurality of 5 times about each loop adjacent each pin, and means for indexing said member one pin space intermediate each rotation thereof.

6. A machine for fashioning a cord base directly on the end of a valve stem comprising a valve 10 stem holding member having a plurality of circumferentially spaced slidable pins arranged concentrically with respect to the stem, means for projecting one of said pins beyond the end of said member farther than the remainder of said pins, 15 means for intermittently rotating said member through a complete revolution to successively wrap a cord about the valve stem and each of said pins to form a plurality of radially extending loops, and means for indexing said member one 20 pin space intermediate each rotation thereof to progressively cause each pin to be projected beyond the end of the member farther than the other pins.

7. A machine for fashioning a cord base directly 25 on the end of a valve stem comprising a valve stem holding member having a plurality of circumferentially spaced slidable pins arranged concentrically with respect to the stem, means for projecting one of the pins beyond the end of said member farther than the remainder of the pins, 30 means for intermittently rotating said member through a complete revolution to successively wrap a cord about the valve stem and each of said pins, means for indexing said member one pin 35 space intermediate each rotation thereof to progressively bring each pin into position where it will be projected the farthest beyond the end of the member, and means for gradually moving said member endwise during the operation of the machine.

8. A machine for fashioning a cord base directly 40 on the end of a valve stem comprising a valve stem holding member having a plurality of circumferentially spaced slidable pins arranged concentrically with respect to the stem, means for projecting one of said pins beyond the end of the member farther than the remainder of the pins, 45 means for intermittently rotating said member through a complete revolution to successively wrap a cord about the valve stem and each of said pins to form a plurality of radially extending loops, means for turning a second cord a plurality of times about each loop adjacent each pin, and means for indexing said member one pin 50 space intermediate each rotation thereof to progressively bring the pins into a position where each pin will project farther beyond the end of the member than do the remainder of the pins.

9. A machine for fashioning a cord base directly 55 on the end of a valve stem comprising a valve stem holding member having a plurality of circumferentially spaced slidable pins arranged concentrically with respect to the stem, means for projecting one of said pins farther beyond the end 60 of said member than the remainder of the pins, means for intermittently rotating said member through a complete revolution to successively wrap a cord about the valve stem and each of said pins to form a plurality of radially extending loops, means for turning a second cord a plurality of 65 times about each loop adjacent each pin, means for indexing said member one pin space intermediate each rotation of the member and each 70 operation of said last named means to progressively move the pins into position where each will 75

be projected farther than the other pins, and means for gradually moving said member endwise during the operation of the machine.

10. A machine for fashioning a cord base directly 5 on the end of a valve stem comprising a valve stem holding member having a plurality of circumferentially spaced slidable pins arranged concentrically with respect to the stem, a cam normally rotatable with said member but capable of rotation relative thereto engaging the ends of 10 said pins and acting to project the opposite end of one of said pins axially beyond said member a greater distance than the ends of the remainder of the pins are projected, means for intermittently rotating said member and cam through a complete revolution to successively wrap a cord about 15 the valve stem and each of said pins to form a plurality of radially extending loops, and means for indexing said member relative to said cam and intermediate each rotation of the member 20 and cam one pin space to progressively project each pin a greater distance than the remainder of the pins.

11. A machine for fashioning a cord base directly 25 on the end of a valve stem comprising a valve stem holding member having a plurality of circumferentially spaced pins arranged concentrically with respect to the stem, means for intermittently rotating said member through a complete revolution to successively wrap a cord about 30 the valve stem and each of said pins, means for indexing said member one pin space intermediate each rotation thereof, and means for gradually moving said member endwise during the operation of the machine and including a cam, and a 35 cooperating abutment carried by said member and rotatable therewith.

12. A machine for fashioning a cord base directly 40 on the end of a valve stem comprising a valve stem holding member having a plurality of circumferentially spaced pins arranged concentrically with respect to the stem, means for intermittently rotating said member through a complete revolution to successively wrap a cord about 45 the valve stem and each of said pins, means for indexing said member one pin space intermediate each rotation thereof and including a pawl and a ratchet rotatable with said member, and means for gradually moving said member endwise during the operation of the machine and including a cam, and an abutment rotatable with 50 said member.

13. A machine for fashioning a cord base directly 55 on the end of a valve stem comprising a valve stem holding member having a plurality of circumferentially spaced pins arranged concentrically with respect to the stem, means for intermittently rotating said member through a complete revolution to successively wrap a cord about 60 the valve stem and each of said pins to form a plurality of radially extending loops, means for turning a second cord a plurality of times about each loop adjacent each pin, means for indexing said member one pin space intermediate each rotation thereof and when said last 65 named means is inoperative, and means for gradually moving said member endwise during the operation of the machine and including a cam, and a cooperating abutment carried by said member and rotatable therewith.

14. A machine for fashioning a cord base directly 70 on the end of a valve stem comprising a valve stem holding member having a plurality of circumferentially spaced pins arranged concentrically with respect to the stem, means for in- 75

- termittently rotating said member through a complete revolution to successively wrap a cord about the valve stem and each of said pins to form a plurality of radially extending loops, means for 5 turning a second cord a plurality of times about each loop adjacent each pin, means for indexing said member one pin space intermediate each rotation thereof and when said last named means is inoperative and including a pawl and a ratchet 10 rotatable with said member, and means for gradually moving said member endwise during the operation of the machine and including a cam and an abutment rotatable with said member.
15. A machine for fashioning a cord base directly on the end of a valve stem comprising a valve stem holding member having a plurality of circumferentially spaced slidable pins arranged concentrically with respect to the stem, means for projecting one of said pins farther beyond the 20 end of said member than the remainder of the pins and including a cam normally rotatable with

said member but capable of rotation relative thereto and engaging the ends of said pins, means for intermittently rotating said member through a complete revolution to successively wrap a cord about the valve stem and each of said pins to 5 form a plurality of radially extending loops, means for turning a second cord a plurality of times about each loop adjacent each pin, means for indexing said member relative to said cam one pin space intermediate each rotation of the member and when said last named means is idle to progressively move the pins into position where each will be projected farther than the other pins, said indexing means including a pawl and a ratchet rotatable with said member, and means 10 for gradually moving said member endwise during the operation of the machine and including a cam and an abutment rotatable with said member.
